CLAIM

The ornamental design for a glass cutter, as shown and described.

DESCRIPTION

FIG. 1 is a top perspective view of a glass cutter, showing the new design;

FIG. 2 is a bottom perspective view thereof;

FIG. 3 is a top view thereof, wherein the armature is in an alternate position;

FIG. 4 is a bottom view thereof;

FIG. 5 is a left side view thereof;

FIG. 6 is a right side view thereof, wherein the armature is in the alternate position;

FIG. 7 is a front view thereof; and,

FIG. 8 is a rear view thereof, wherein the armature is in the alternate position.

The broken lines depict portions of the glass cutter in which the design is embodied that are not considered part of the claimed design.
